UNITED STATES PATENT OFFICE.

FREDERICK T. MAYNARD, OF DETROIT, MICHIGAN, ASSIGNOR TO THE
DETROIT LAWN MOWER COMPANY, OF SAME PLACE.

DESIGN FOR A FRAME FOR LAWN-MOWERS.

SPECIFICATION forming part of Design No. 26,286, dated November 17, 1896.

Application filed June 6, 1896. Serial No. 594,629. Term of patent 14 years.

To all whom it may concern:

Be it known that I, FREDERICK T. MAYNARD, a citizen of the United States, residing at Detroit, in the county of Wayne and State 5 of Michigan, have invented and produced a new and original Design for Lawn-Mower Frames, of which the following is a specification, reference being had therein to the accompanying drawing, in which the figure is 10 a perspective view of the frame.

The leading feature of my design is the configuration of the frame and of the side bars thereof. The side bars comprise the circular disk A, the plate B, parallel therewith, 15 and the intermediate curved connection C. On the disk and forming practically a continuation of the curved connection C is the

raised boss D, its rear end terminating in a graceful curve or being rounded, as shown. The bosses D on the two side bars are connected by the cylindrical tube E, centrally of which is the enlarged cylindrical casing F.

What I claim as my invention is—

1. In a design for a lawn-mower frame, the side bar, substantially as shown and described.

2. The design for a lawn-mower frame substantially as herein described and shown.

In testimony whereof I affix my signature in presence of two witnesses.

FREDERICK T. MAYNARD.
